UNITED STATES PATENT OFFICE

RAYMOND E. ACKLEY, OF CHICAGO, ILLINOIS, ASSIGNOR TO R. R. DONNELLEY & SONS CO., OF CHICAGO, ILLINOIS, A CORPORATION OF ILLINOIS

TIMING DEVICE FOR GATHERING AND BINDING MACHINES

Application filed May 10, 1929. Serial No. 362,060.

My invention relates to mechanism for use in connection with two independent article-conveyors with which the articles are engaged in succession and the first one of which 5 conveyors may be traveling at a speed not in excess of the speed of the second conveyor, to engage the articles and be operative to transfer them from the first conveyor to the second conveyor and cause the articles to be put in 10 step with mechanisms having a timed relation to the movement of the second conveyor.

While my invention is applicable to arrangements in general of the character above stated, I have devised it for use more particularly 15 in connection with the manufacture of books and involving the use of so-called signature-gathering machines and co-operating book-binding machines, the signature-gathering machines operating to assemble 20 the various signatures into the proper positions to constitute the books and the book-binding machines, to which the grouped signatures are delivered, operating to bind the books.

25 The signature-gathering machines are commonly provided with mechanisms whereby should the devices which operate to deliver the signatures to the signature-assembling points fail to deliver a signature, or should 30 a signature, imperfect because of an excess, or deficiency, of sheets, be delivered, the signature-gathering machine automatically stops. Furthermore, the binding-machines involve, as elements thereof, mechanisms for 35 applying glue to the edges of the grouped signatures for cementing thereto the covers applied by the binding-machines. Such conditions, in particular, have given rise to 40 considerable difficulty in the book-binding operation where the conveyor mechanisms of the signature-gathering machines and the binding-machines start and stop simultaneously, owing to the fact that delay in resuming the operations of the machines is 45 oftentimes so prolonged that the glue applied to the grouped signatures, and before the covers have been applied thereto and properly adhered, becomes set, requiring the removal 50 of those of the grouped signatures on which the glue has hardened as stated and the com-

pletion of the binding of the books by manual operations.

It will be apparent from the foregoing that it is desirable provision be made for permitting the binding-machine to continue in 55 operation and bind such of the grouped signatures as have been produced by the signature-gathering machine, after the latter has stopped, as for example because of the failure of the delivery of a signature, or the 60 delivery of an imperfect one, and thus render unnecessary operation on the books by hand as above stated, and to provide for the proper delivery to the book-binding machine, namely, in step with the operations of the various 65 mechanisms of the book-binding machine, of the grouped signatures delivered by the signature-gathering machine upon re-starting the latter.

70 Previous attempts have been made to overcome this difficulty, by providing a so-called one-point clutch, or clutch which will engage in only one position, between the two machines so that when the gathering machine stops this clutch automatically disengages 75 and allows the binder to continue in motion, and when the gathering machine is to be started this clutch is re-engaged and the binder picks up the gathering machine drive in proper timed relation. Owing to the need 80 of engaging the clutch at a definite point, however, it cannot be engaged gradually, and there is a severe objectionable shock to the mechanisms whenever it is operated.

85 The primary object of my invention is to provide mechanism whereby the articles may be delivered, to a second, succeeding, conveyor, as for example the conveyor of a book-binding machine, in timed relation to the mechanism, or mechanisms, operated in timed 90 relation to such second conveyor, regardless of interruptions in the operation of the conveyor first engaging the articles, as for example that of a signature-gathering machine.

95 Another object is to provide for the properly timed operations of the gathering machine and the binder by timing the books instead of timing the machines.

100 Another object is to provide a mechanism, intermediate two article-carrying conveyors,

the second of which must operate in timed relation to mechanisms placed along its path, such that any article delivered by the first conveyor will be placed in proper timed relation to the second conveyor, provided only that the first conveyor does not deliver more articles in a given time than the second conveyor can carry away. Thus the first conveyor may operate continuously or intermittently, it may travel at any speed desired and it is not essential that it deliver an article at the moment when the second conveyor is in proper position to receive it. In short, the first conveyor may operate with complete disregard of the timing of the second conveyor, the only restriction being that it must not deliver more articles in a given time than the second conveyor can take.

Another object is to provide novel, simple and positively operating mechanism for the purpose stated; and other objects will be manifest from the following description.

Referring to the accompanying drawings:

Figure 1 is a view in side elevation of the adjacent ends of a signature-gathering machine and a book-binding machine, together with transfer mechanism constructed in accordance with my invention, operating to transfer the grouped signatures from the gathering machine to the book-binding machine.

Figures 2, 3 and 4 are enlarged sections taken at the lines 2, 3 and 4, respectively, on Fig. 1 and viewed in the direction of the respective arrows.

Figure 5 is a plan view of a portion of the conveyor chain shown in Fig. 3.

Figure 6 is an enlarged, broken, plan view of a portion of a conveyor operated by the signature-gathering machine and of one end portion of the transfer mechanism.

Figure 7 is a perspective view of a portion of the conveyor of Figs. 2, 3 and 4, and comprising one of the similar pusher-arms shown by full and dotted lines in two positions occupied by it in operation.

Figure 8 is a similar view of a portion of the transfer mechanism showing one of the similar arms by which the grouped signatures are advanced to the book-binding machine.

Figure 9 is an enlarged plan sectional view of one end of the book-binding machine and the adjacent portion of the transfer mechanism.

Figure 10 is a perspective view of one end of the conveyor of the book-binding machine and the mechanism by which it is operated.

Figure 11 is a view in side elevation of a portion of the transfer mechanism; and

Figure 12, a broken perspective view of the transfer mechanism of Fig. 11.

In the particular arrangement illustrated, my invention is associated with a signature-

70 gathering machine and a book-binding machine to transfer the grouped signatures from the signature-gathering mechanism to the book-binding mechanism in step with the operation of the various mechanisms of the latter, the gathering machine being represented generally at 14 and the book-binding machine at 15.

75 The signature-gathering machine may be of the type hereinbefore referred to, to produce the grouped signatures represented at 16 and comprising the contents of the books to be bound, and as such machines are well-known detailed illustration and description thereof appear to be unnecessary.

80 The delivery end only of the signature-gathering machine is shown, the conveyor by which the signatures, during the operation of grouping them for subsequent binding and after grouping, are conveyed along the trough represented at 17 of the gathering machine, being shown at 18, this conveyor, provided with pusher-arms 19, and tilted at an angle to the vertical, as represented in Fig. 2, engaging sprockets, one only of which is 85 shown at 20, at opposite ends of the gathering machine.

90 The conveyor 18 is driven by the main shaft 21 (Fig. 2) of the gathering machine through a bevel gear 22 on shaft 21, engaging a bevel gear 23 on one end of a shaft 24, and a bevel gear 25 on the opposite end of shaft 24, engaging a bevel gear 26 on shaft 27 of the sprocket 20.

95 Arranged in line with the trough 17, and in accordance with common practice, is a trough-section 29 for receiving the groups of signatures delivered by the conveyor 18, this trough-section being so shaped that as the groups of signatures are conveyed through it, by mechanism hereinafter described, they are gradually shifted from a position in which they extend at the angle to the vertical as shown in Fig. 2, to a position in which they extend vertically, with the edge-portions thereof at which the signatures of each book are to be bound together, lowermost as represented, the lateral walls of that portion of the trough section 29 which is vertical being formed of vertically spaced horizontal bars 29^a which exert slight pressure against the opposite sides of the groups of signatures.

105 The conveyor for moving the groups of signatures in the trough-section 29 up to the point where the transfer mechanism herein-after described engages them, is represented at 30 and is in the form of an endless-chain 110 engaging sprockets at its opposite ends, one only of which is shown at 31, this sprocket being driven by a vertical shaft 32 thereof in the frame of the machine and provided with a worm-gear 33 meshing with a worm 34 on the shaft 21 of the gathering machine.

115 The chain of the conveyor 30 is provided at intervals with pusher-arms 35, which are 120

pivoted at 36 to pins 37, so that the arms 35 can swing up and down freely. The pins 37, in turn, are journaled at 38, on vertical axes, in blocks 39 secured to chain 30, so as to permit of a turning movement of the pins 37 in a plane at right angles to that of the arms 35 about the pivots 36. To the lower ends of the pins 37 are fastened blocks 40 which carry, at 41, lugs which abut against projecting surfaces 42 of chain 30. This arrangement prevents pins 37 from swinging in one direction but allows them to be free to swing in the other direction, so that the arms 35 can be caused to drive articles in the direction of motion of conveyor 30, but if an article moving at a greater rate of speed than conveyor 30 approaches from behind an arm 35 the latter will swing out of the way and permit it to pass. The arms 35 travel in slots 29^b in the trough 29, and swing down as they are advanced through the trough section 29 up to the point where the trough side-walls are vertical, and are maintained during engagement with the groups of signatures in a position substantially normal to the plane of the groups of signatures with which they are engaged.

As later described, under some conditions of operation of the machine, the pins 35 will be swung around into a position more or less parallel to conveyor 30, as indicated of the pin 35 nearest the bottom of Fig. 5. When this happens it is necessary to restore them to a position at right angles to conveyor 30, before engaging a signature-group 16. For this purpose I provide a pin 43 mounted on a stationary bracket 44 attached to the frame of the machine. The position of pin 43 is such that whenever arm 35 has been swung about, as described, the pin 43 is engaged by block 40 attached to the lower end of pin 37 carrying the arm 35, and the block 40 is thus cammed back into a position parallel to conveyor 30 which causes the arm 35 to assume a position at right angles to conveyor 30 as shown at the top of Fig. 5.

While the conveyor 30 is provided as an element separate from the conveyor 18 this is not necessary in the practicing of my invention, and in the case of its omission the conveyor 18 would be provided preferably with pivoted pusher-arms as in the case of conveyor 30 and the conveyor 18 extended to the position corresponding to that of the right-hand terminal (Fig. 1) of the conveyor 30.

Referring now to the binding machine 15 in which the groups 16 of signatures are bound to form the books, the signature-groups 60 to this end being operated on by a plurality of mechanisms (not shown), in succession, and which may be the mechanisms as shown and described in my United States Letters Patent No. 1,704,454, granted March 5, 1929, the machine comprises a main drive-shaft 45 which

operates the several mechanisms referred to, of the book-binding machine and functioning to bind the book; and also a conveyor 46 and pairs of endless presser-belts 47 to which the conveyor 46 delivers the groups of signatures 79 in timed relation to the operation of the several mechanisms by which the books are bound, the belts 47 also operating in timed relation to such mechanisms.

The conveyor 46 is shown as formed of an endless chain 48 mounted on sprockets 49 and 50 journaled on the machine to rotate on horizontal axes and having pusher elements 51, the drive of chain 48 being from the main shaft 45 of the binding machine through a shaft 52 geared at 53 and 54 to shaft 45 and at 55 and 56 to the shaft 57 of sprocket 50.

As regards the matter of the relative speeds of travel of the conveyor for the gathering machine and the book-binding conveyor, the relative linear speed of these conveyors is not important; but in the sense of the number of books handled the binder must, if anything, be constructed to handle them faster as otherwise the binder would be choked by delivering of books to it faster than it is capable of handling. By way of example, and in the machine as shown, the gathering-machine conveyor 18 would travel in proportion to the travel of the book-binder conveyor 46 in a ratio of about 21½ to 18.

In the arrangement shown the transfer mechanism, hereinbefore referred to, is provided to receive the groups of signatures from the conveyor 30 and so deliver them that they will become engaged by the pusher-elements 51 of conveyor 46 and then by the presser belts 47 and thus advanced into, and through, the binding-machine 15 in properly timed relation to the several mechanisms thereof which operate, successively to produce the finished book.

The transfer mechanism comprises a pair of sprockets 58 and 59 journaled on brackets on the machine to rotate on horizontal axes, the journals of these sprockets being located above the plane of the upper edges of the groups of signatures as the latter travel in the trough-section 29 to the binding machine and the sprockets being located to one side of said trough-sections.

Engaging the sprockets 58 and 59 is an endless sprocket-chain 60 this chain being driven from the shaft 45 by a sprocket-chain 61 in driving engagement with sprockets provided, respectively, on the shaft 45 and on a shaft 62 journaled on the machine, and bevel gear connection, comprising gears 63 and 64 on the shaft 62 and the stub-shaft 65 of the sprocket 58, respectively.

The transfer mechanism also comprises a series of conveyor-arms 66 journaled on blocks 67 secured to the chain 60 at equal distances therealong, these arms being shown as in the form of cranks at the horizontal crank-

portions 68 of which the signature groups are engaged for effecting transfer thereof by this mechanism, the outer ends of the cranks extending laterally beyond the sides of the signature-groups 16, as shown in Fig. 9.

The operation of the transfer mechanism is as follows: The transfer conveyor 60 travels at a greater linear speed than the conveyor 30, and over a portion of their length the two conveyors are overlapped as shown in Fig. 1. The amount of the overlap is such that in traversing this distance, the transfer conveyor 60 gains an amount over the conveyor 30 approximately equal to the distance between two pins 35 on conveyor 30. As an example, the conveyor 30 may move 18", the distance between two pins 35, while transfer conveyor 60 moves 21", the distance between two cranks 68. In this case there will be a precession of 3" of the conveyor 60 over the conveyor 30 every time the latter moves 18". If the overlap is nine feet, the precession in that distance will amount to 18". It will be obvious that a similar result may be accomplished at other relative speeds.

No matter what the position of an arm 35 on conveyor 30 may be as it approaches the entrance to transfer conveyor 60, that crank 68 on conveyor 60 which is at the moment behind the arm 35, will by reason of this precession, overtake and pass arm 35 at some time during traverse of the overlapped portions of the two conveyors. Then, if arm 35 is delivering a signature group through 29, and if crank 68 is caused to engage the signature group, as hereafter explained, at the moment it passes arm 35, the signature-group will thence be picked up and carried forward by conveyor 60. Thus each succeeding signature-group is taken away from an arm 35 on conveyor 30 by a crank 68 on conveyor 60, and delivered by the latter to a pusher bar 51 on conveyor 48 for delivery to the traveling belts 47 in timed relation to the various mechanism of the book-binding machine. By this means the gathering machine and its delivery conveyor 30 may be started, stopped, and otherwise operated with entire independence from the binder, with the exception that it must not deliver more books in a given time than can be passed through the binder.

Conveyor 46 and presser belts 47 may be operated at the same linear speed as the transfer-conveyor, or faster or slower, as may be desired (but always in 1:1 cyclical relation), but in practice I prefer to run conveyor 46 somewhat slower than transfer-conveyor 60. In that event, I prefer to place sprocket 49 a calculated distance behind sprocket 58, by which means advantage is taken of the fact that in passing around sprocket 58, the motion of crank 68 becomes divided into a decreasing horizontal component and an increasing vertical component, so that a signa-

ture-group moved by crank 68 suffers a progressive slowing down. By properly choosing the relative positions of sprockets 49 and 58 the signature-group may be delivered to bar 51 on conveyor 48 while traveling at substantially the same speed as the latter.

It is evident that when the signature-groups are in certain positions at the moment they approach the transfer that crank 68 will engage the successive groups at once or within a short distance of the entrance of the transfer, in which case the precession of crank 68 after engagement will be great enough to cause the front margin of the signature-group to approach and strike the arm 35 on conveyor 30 which is just ahead of it. As before described, in this event the journalling of pin 37 in block 39 allows arm 35 to swing out of the way and allows the signature-group to pass. The engagement of the cranks 68 with the signature-groups 16 may be effected in any desirable way, as for example, by the means shown in the drawings and by which the arm 68 is prevented from dragging over the top margins of the signature-group and therefore there is no tendency to disarrange the signatures.

By way of summarizing the relative speeds of movement of the various conveyors, it may be stated that according to the particular arrangement shown and described, the signature groups undergo the following changes of speed in passing from the gathering machine to the binding machine: The gathering machine conveyor 18 travels at about 21½" per cycle. The take-away conveyor 30 travels at 18" per cycle. The transfer conveyor 60 at 21" per cycle and the feed conveyor 46 and presser belts 47 at 18" per cycle. For reasons peculiar to the gathering machine 14, more space is required between the signature groups than is required on the binding machine 15, therefore the pins 19 on conveyor 18 are placed about 21½" apart. In passing from the conveyor 18 to the conveyor 30 the speed of the signature group is reduced to 18" per cycle the same as the binding machine; the difference in speed between the conveyor 30 and the conveyor 60 being essential to the operation of my invention.

The means referred to comprise upwardly extending pins or blocks 75 attached to conveyor 30, and which may be merely the extended ends of pins 37 (see Fig. 11). On the conveyor 60, adjacent each arm 66, is fastened a block 76 (Fig. 12) in which is journalled a pin 77, in the outer end 78 of which is mounted a latch, or trip, rod 79. A torsion spring 80 acting between block 76 and the pin-end 78, tends to force the rod 79 in the direction indicated by the arrow in Fig. 12. The upper end of the rod 79 is provided with a saddle 81, adapted to receive and support the crank 68 of the adjacent arm 66. The crank 68 is prevented from coming into

engagement, either with the lower portion of bar 69 or with the upper margin of a signature-group beneath it until the trip 79 is operated. The lower end of trip 79 is extended as shown at 82 and is so disposed that it engages an adjacent pin 75 on the conveyor 30, whenever the relative movement of conveyors 60 and 30 is such that the trip rod 79 passes pin 75. When this occurs, the trip 10 79 is displaced into the position indicated by dotted lines in Fig. 11, thus allowing the crank 68 to fall upon bar 69. This action always takes place when crank 68 falls between two adjacent signature-groups 16. By 15 this means the necessity of dragging the crank 68 over the top margins of the signature groups is avoided.

In order to restore the cranks 68 to the latched position, a stationary guide bar 83 (Fig. 1) is provided for engagement by the outer ends of the cranks 68, this bar being of such shape and so positioned, as shown, that the conveyor arms 66 are swung to a position in which the trip-rods 79, under the action 20 of their springs 80, reengage at their saddles 81 with the cranks 68.

It will be noted that, while I have illustrated and described several conveyors as forming parts of a train of mechanism, the 25 timing of the article is completely effected by the interaction of the two conveyors 30 and 60. Functionally, therefore, conveyor 30 might be the main conveyor of a gathering machine, and 60 the main conveyor of a binding machine. I, therefore, do not wish 30 to be confined to the precise arrangement described, but claim as my invention any mechanism including a pair of conveyors functionally related in the manner of conveyors 35 30 and 60.

Furthermore, the machine shown may be variously modified and altered in other ways without departing from the spirit of my invention, and in this connection it may be 40 stated that while it is desirable that mechanism, such for example as that shown and described, be employed for preventing the dragging of the cranks 68 over the top margins of the signature groups, provision of 45 mechanism for this purpose is not essential to my invention.

What I claim as new, and desire to secure by Letters Patent, is:

1. In combination, a pair of adjacent independently driven conveyors, one of which has a greater linear speed than the other, and article-engaging means carried by each conveyor and operating to transfer the article from the slower to the faster conveyor whenever the article-engaging means carried by the faster moving conveyor passes the article-engaging means carried by the slower moving conveyor.

2. In an article-timing device, a continuously moving conveyor having timed rela-

tion to mechanisms with which it cooperates, an adjacent independently driven conveyor moving at a lesser linear speed than said first-named conveyor, a support along which articles may be moved, and article-engaging 70 means carried by each of said conveyors, said conveyors being so disposed that the article-engaging means on said first-named conveyor engage an article delivered by the article-engaging means carried on said second-named conveyor, whenever the article-engaging means on said first-named conveyor pass the article-engaging means on said second-named conveyor.

3. In combination, conveyor mechanisms 80 for successively engaging and conveying articles and operating without definite timed relation to each other, and means intermediate said conveyors, and operative without stopping the motion of the articles, for receiving 85 the articles irrespective of the timing of either conveyor, and delivering the same to the second one of said conveyors in timed relation to the latter.

4. In combination, conveyor mechanisms 90 operative to successively engage and convey articles and which operate without definite timed relation to each other, a third conveyor traveling adjacent to the first conveyor but at a higher speed and in timed relation to 95 the second conveyor, and means whereby the third conveyor receives articles delivered by the first conveyor irrespective of the timing of said articles and delivers them in properly timed relation to the movement of the second 100 conveyor.

5. In combination, conveyor mechanisms 105 operative to successively engage and convey articles and which operate without timed relation to each other, and means operative 110 to receive the articles delivered by the conveyor first to operate thereon and deliver them to the other of said conveyor mechanisms in properly timed relation to the movement of the latter.

6. In combination, a signature-gathering machine comprising conveyor means and means for delivering the signatures to said conveyor means, a book-binding machine operative independently of said signature-gathering machine comprising conveyor means and mechanism operating on the articles successively and operated in timed relation to said second-named conveyor-means, and means operative to receive the articles delivered by said first-named conveyor means and deliver them to the other of said conveyor means in properly timed relation to the movement of the latter regardless of the relative positions occupied by said conveyor 120 means when simultaneous actuation of said machines is initiated.

7. In combination, conveyor mechanisms 125 operative to successively engage and convey articles and which operate out of timed re-

lation to each other, and a conveyor operating at a greater speed than the one of said first-named conveyor mechanisms to which the other of said conveyor mechanisms delivers the articles and operative to receive the articles from the one of said conveyor mechanisms first to operate thereon and deliver them to the other of said conveyor mechanisms in properly timed relation to the movement of the latter.

8. In combination, conveyors operating to successively engage and convey articles, said conveyors operating out of timed relation to each other and the one of said conveyors first to operate on the articles operating at a lesser speed than the other of said conveyors and a third conveyor operating at a greater speed than the one of said first-named conveyors to which the other of said conveyors delivers the articles and operative to receive the articles from the one of said conveyors first to operate thereon and deliver them to the other of said conveyor mechanisms in properly timed relation to the movement of the latter.

9. In combination, a pair of adjacent driven conveyors one of which has a greater linear speed than the other, and article-engaging means carried by each conveyor, said article-engaging means being so disposed that the article is transferred from the engaging means of said slower operating conveyor to the engaging means of the faster operating conveyor without regard to the relative timing of the article-engaging means of the several conveyors.

10. In combination, a pair of adjacent driven conveyors one of which has a greater linear speed than the other, and article-engaging means carried by each conveyor, said article-engaging means being so disposed that the article is transferred from the engaging means of said slower operating conveyor to the engaging means of the faster operating conveyor by the article-engaging means carried by the faster moving conveyor passing the article-engaging means carried by the slower moving conveyor.

11. In combination, a pair of driven conveyors one of which has a greater linear speed than the other, and article-engaging means on each conveyor, both of said means being so disposed that the articles presented thereto extend into the path of movement of said means, said conveyors being relatively lapped such a distance and the differential speed of movement of said conveyors being such that the article-engaging means on the faster moving one of said conveyors in moving along the lapped portions of the conveyors moves a distance at least approximately equal to the distance between adjacent ones of the article-engaging means on the slower moving one of said conveyors.

12. An article-timing device comprising

two conveyors one of which travels faster than the other thereof and the paths of which have overlapping relationship to each other, and means comprising article-engaging means on each of said conveyors whereby the article is transferred from the slower moving conveyor to the faster moving conveyor whenever the article-engaging means carried by the faster moving conveyor pass the article-engaging means carried by the slower moving conveyor, said article-engaging means being adapted to convey an article along a path common to both of said conveyors and either of which may convey the article along said common path, the length of said common path and the relative speeds of said conveyors being such that during the continuance of said common path the faster moving conveyor gains over the slower moving conveyor an amount approximately not less than the greatest possible linear separation of the article-engaging means carried by the faster moving conveyor from the article-engaging means carried by the slower moving conveyor.

13. In combination, a pair of adjacent driven conveyors one of which has a greater linear speed than the other, and article-engaging means carried by each conveyor, said article-engaging means being so disposed that the article is transferred from the engaging means of said slower operating conveyor to the engaging means of the faster operating conveyor when the article-engaging means carried by the faster moving conveyor passes the article-engaging means carried by the slower moving conveyor, the article-engaging means of the slower moving conveyor being adapted to yield in the direction of movement of the articles, for the purpose set forth.

14. In combination, a pair of adjacent driven conveyors one of which has a greater linear speed than the other, and article-engaging means carried by each conveyor, said article-engaging means being so disposed that the article is transferred from the engaging means of said slower operating conveyor to the engaging means of the faster operating conveyor when the article-engaging means carried by the faster moving conveyor passes the article-engaging means carried by the slower moving conveyor, the article-engaging means of the slower moving conveyor being pivoted to said conveyor to adapt them to yield in the direction of movement of the articles, for the purpose set forth.

15. In combination, a pair of adjacent driven conveyors one of which has a greater linear speed than the other, and article-engaging means carried by each conveyor, said article-engaging means being so disposed that the article is transferred from the engaging means of said slower operating conveyor to the engaging means of the faster operating conveyor when the article engag-

ing means carried by the faster moving conveyor passes the article-engaging means carried by the slower moving conveyor, and means operating to prevent the article-engaging means on the faster moving one of said conveyors from engaging the upper edges of the articles.

16. In combination, a pair of adjacent driven conveyors one of which has a greater linear speed than the other, and article-engaging means carried by each conveyor, said article-engaging means being so disposed that the article is transferred from the engaging means of said slower operating conveyor to the engaging means of the faster operating conveyor when the article-engaging means carried by the faster moving conveyor passes the article-engaging means carried by the slower moving conveyor, and means controlled by the article-engaging means on the slower one of said conveyors for preventing the article-engaging means on the faster moving one of said conveyors from engaging the upper edges of the articles.

17. In combination, a pair of adjacent driven conveyors one of which has a greater linear speed than the other, and article-engaging means carried by each conveyor, said article-engaging means being so disposed that the article is transferred from the engaging means of said slower operating conveyor to the engaging means of the faster operating conveyor when the article-engaging means carried by the faster moving conveyor passes the article-engaging means carried by the slower moving conveyor, the article-engaging means on the faster moving conveyor being pivoted to the latter, and means operating to prevent the article-engaging means on the faster moving conveyor from swinging into engagement with the upper edges of the articles.

18. In combination, a pair of adjacent driven conveyors one of which has a greater linear speed than the other, and article-engaging means carried by each conveyor, said article-engaging means being so disposed that the article is transferred from the engaging means of said slower operating conveyor to the engaging means of the faster operating conveyor when the article-engaging means carried by the faster moving conveyor passes the article-engaging means carried by the slower moving conveyor, the article-engaging means on the faster moving conveyor being pivoted to the latter; and means controlled by the article-engaging means on the slower moving conveyor for preventing the article-engaging means on the other of said conveyors from swinging into engagement with the upper edges of the articles.

RAYMOND E. ACKLEY.
